United States Patent Office.

ELIJAH W. BIGELOW, OF WORCESTER, MASSACHUSETTS.

Letters Patent No. 91,598, dated June 22, 1869.

STOVE-TOP AND COVER

The Schedule referred to in these Letters Patent and making part of the same.

Know all men by these presents:

That I, ELIJAH W. BIGELOW, of the city and county of Worcester, and Commonwealth of Massachusetts, have invented certain new and useful Improvements in Stove-Tops and Covers; and I do hereby declare that the following is a full, clear, and exact description of the same, reference being had to the accompanying drawings, forming a part of this specification, in which—

Figure 1 represents a perspective view of my improved stove-top and cover, the latter being closed.

Figure 2 represents a perspective view of the same, with the cover open.

Figure 3 represents a transverse section on line A B, fig. 1.

To enable those skilled in the art to which my invention belongs, to make and use the same, I will describe it more in detail.

The nature of my invention consists, first, in an improved mode of combining a swinging or hinged cover with the top of the stove, as will be hereafter explained.

Also, in the combination, with a hinged or swinging cover, of a hinged ornamental cap or top, as will be hereafter set forth.

In the drawings—

A represents the top of the stove, in which is formed an opening, B, in the usual manner.

A swinging or hinged cover, C, is secured to the top A by a pivot-bolt or screw attached to the projection D, whereby the cover C may be moved away from the opening B, for feeding the stove, or for other purposes, when desired. (See fig. 2 of the drawings.)

The swinging cover C has an opening in the centre, which, in turn, is closed with a cover, E, while to the rear edge of the swinging or hinged cover C, is hinged an ornamental top or cap, F, by means of the peculiarly-constructed hinge G, as shown in the drawings.

The top parts 1 1 of the hinge G, which are fastened to the ornamental top F, are provided with projections or spurs α on their lower ends, which rest or strike against the edge of the sliding cover C, as shown

in red lines, fig. 3, when the ornamental top or cap F is raised, whereby the ornamental top or cap F is prevented from falling over back when turned up, as shown in fig. 2.

A rim, b, is formed upon the top of the stove A, around the opening B, which fits the inner side of the flange c, at the edge of sliding cover C, and retains the latter in position when closed, while at the same time a neater and more finished appearance is given to the stove than would be the case if the flange or rim were arranged to fit the outside of flange c.

The top F may be made of any desired pattern to suit the taste, and may be surmounted by an urn or ornamental handle, d.

The joint of the cover C is made loose enough to admit of a slight up-motion of the cover sufficient to allow it to be raised to pass over the rim or flange b, after which it fits down upon the top plate A, and outside of rim b, as shown in fig. 3 of the drawings.

My present improvements are very important when considered in a practical point of view, since they obviate the necessity of holders and lifting-tongs and irons for the purpose of removing the ornamental cap; and besides, there is no danger of the ornamental top or cap falling off when the cover C is turned around.

Having described my improvements in stove-tops and covers,

What I claim therein as new, and of my invention, and desire to secure by Letters Patent, is—

1. The combination and relative arrangement, with the top plate A and rim b, of the hinged cover C, with outer flange c, substantially as shown and described.

2. The combination, with the hinged or swinging cover C, of the hinged ornamental top F, substantially as and for the purposes set forth.

3. The combination, with the hinged cover C and hinged ornamental top F, of a projection, α , substantially as and for the purposes set forth.

E. W. BIGELOW.
